FLYING MACHINE

Filed Dec. 15, 1925

FIG. 1.

FIG. 2.

FIG. 3.

INVENTOR:

ALLEN J. BUTTLER,

By: Otto de Ruyge
his Atty.

UNITED STATES PATENT OFFICE.

ALLEN J. BUTTLER, OF LOS ANGELES, CALIFORNIA.

FLYING MACHINE.

Application filed December 15, 1925. Serial No. 75,572.

This invention relates to devices used on flying machines for carrying the flying machine in case of engine trouble.

One of the objects of this invention is to provide an emergency source of power independent of the regular driving mechanism of an aeroplane.

Another object is to provide emergency vanes to increase the carrying facilities of a flying machine operative and effected by independent power means in case of trouble on the regular driving mechanism of the flying machine.

Another object is to provide an emergency propeller independent of and at a distinct point from the regular propeller, normally in inoperative and protected position, advanced into operative position and operative by and independent power means.

Other objects will appear from the following description and appended claims as well as from the accompanying drawing, in which—

Fig. 1 is a side elevation of a roughly outlined flying machine, with independent propeller and emergency vanes in proper position embodying this invention.

Fig. 2 is an end elevation of the operating mechanism for the emergency propeller and emergency vanes, to illustrate in a somewhat diagrammatical manner the interconnection and co-operation of the propeller and vanes.

Fig. 3 is an enlarged illustration partly in section of the interconnecting driving gear.

The flying machine itself may be of the monoplane or any multiple-vane or other well-known type.

In the drawing, the flying machine is provided with the usual fuselage 4, the main and normally operated propeller 5, the main and normally disposed carrying vanes 6, and rear rudder and steering vanes

7, as illustrated in Fig. 1.

The driving motor for the regular propeller 5 is as usually in the front end 8 of the aeroplane.

In case of engine trouble under these common arrangements, the whole aeroplane is liable to become over-balanced, to result in the much-feared nose-dive and final crash.

To facilitate a balancing and a maintaining of an aeroplane in the air after engine trouble and in case that the regular driving

motor and regular propeller are disabled, an emergency motor, preferably electric motor, is provided, as roughly indicated at 9. This motor 9 is operative by a battery 10 through a switch 11, from a point near the driver's seat.

Auxiliary motor and battery are limited of size, since practically merely used in emergency cases for carrying or bringing the aeroplane safely to the ground or for maintaining the plane properly balanced for a limited distance.

Emergency vanes 12 and 13 are provided to extend forwardly and rearwardly from the main vane or plane 6. These emergency vanes are normally within the contours of the main vanes of an aeroplane, or at least largely so. Connecting rods 14 are pivotally connected to the emergency vanes, operative by an upwardly moving member 15, to which the rods are also pivotally connected.

An emergency propeller 16 is provided shiftable in a practically vertical direction, normally to be in its lowermost position close to, and, as much as the particular structure of an aeroplane allows it, disposed so as to offer little obstruction beyond the contours of the main vanes or planes. Where the structures of particular aeroplanes allow it, a recess is preferable to be provided for this emergency propeller when so in its lowermost position in relation to the main vanes, though not shown in the drawing, since to the most extent depending on the structure of particular aeroplanes.

The up and down movements of the propeller as well as of the member 15 for the emergency vanes 12 and 13 are operative by a common main shaft 17. This main shaft is rotated by means of a belt or other similar transmitting member 18 actuated by the motor 9.

The cooperating and interacting connections between the motor 9 and the emergency propeller and emergency vanes are somewhat diagrammatically but more clearly illustrated in the Figs. 2 and 3. The upward moving member 15 for different emergency vanes is indicated in portions in Fig. 2, and an upward moving member 19 is indicated for similarly supporting for upward movement the emergency propeller 16. Flexible members 20 serve to connect the upward moving members 15 and 19 opera-

tively to the main shaft 17 by means of drums 21, and the shafts 22, as well as the gears 23, which may be worm and worm-gear or spiral gears or other similar suitable means. The coupling 24 is turnably disposed on the main shaft 17, as indicated in Fig. 3, and this coupling serves at the same time as a pulley for the belt 18. A co-acting coupling member 25 is keyed to the main shaft 17, so that the main shaft may receive its rotary motion from the motor 9 whenever the coupling member 24 is moved to engage with the coupling member 25. When so engaged, the motor 9 serves to lift or move the members 15 and 19 upwardly, to bring the emergency propeller 16 and the emergency vanes 12 and 13 into operative position. When the upward moving members reach their uppermost operative position, the contact member 26 on the upward moving member 19 serves to move the yoke lever or coupling controlling member 27 so as to disengage the coupling member 24 from the coupling member 25, and at the same time serves to shift the coupling member 24 so as to engage with the coupling member 28. A spiral gear 29 is in operative connection with the coupling member 28, and at the same time in mesh with a second spiral gear 30, which in turn is slidingly but operatively engaged with the shaft 31, carrying the emergency propeller 16.

This arrangement results in bringing the emergency propeller 16 into operative connection with the motor 9 as soon and after the propeller and emergency vanes have been brought into operative position, so that, after trouble with the main motor and main propeller 5, the emergency vanes in conjunction with the emergency propeller can be made to maintain the aeroplane in operative condition and properly balanced.

I do not limit myself to the particular details of the gearings and other smaller mechanisms, as long as the emergency vanes and emergency propeller can thereby be brought into operative position in the cooperative manner as disclosed herewith, to result in the operation of the emergency propeller in the cooperative manner within the scope of the appended claims and I wish it understood that the smaller details may be changed and substituted by other means accordingly.

Having thus described my invention, I claim:

1. In a flying machine, in combination with the regular driving mechanism and carrying planes, emergency planes and emergency propelling means normally disposed close to the regular carrying planes embodying means by which the emergency planes are shifted forward and rearward of the main and regular carrying planes and by which the emergency propelling means are moved above the regular carrying planes and adapted to rotate the emergency propelling means on reaching operative position. 70

2. In a flying machine, in combination with the main and regular driving mechanism and carrying planes, an emergency driving and operating source independent of the main and regular operating and driving source of the flying machine, shiftable members disposed for movements in up and downward directions in operative connection with the emergency driving and operating source, emergency planes disposed adjacent to the main planes of the flying machine and shiftable to extend beyond the front and rear edges of the main planes and in operative connection with certain of the up and down moving members, and an emergency propeller disposed to rotate in a practically horizontal plane and shiftably supported by certain of the up and down moving members, and means whereby the rotating motion of the emergency driving source may be transmitted to the emergency propeller. 90

3. In a flying machine, in combination with the main and regular driving mechanism and carrying planes, an emergency driving and operating source, transmitting members shiftable in an up and down direction, emergency planes shiftable beyond the front and rear edges of the main planes, an emergency propeller disposed to rotate in a plane 100 practically parallel to the carrying surfaces of the main planes and in operative connection with certain of the transmitting members, and means disposed between the said emergency source and the transmitting members for actuating the emergency planes and propeller. 105

In testimony that I claim the foregoing as my invention I have signed my name.

ALLEN J. BUTTLER.
